United States Patent Office.

ROBERT ROOKE, OF EMPIRE CITY, OREGON.

Letters Patent No. 65,282, dated May 28, 1867.

IMPROVED WASHING MACHINE.

The Schedule referred to in these Letters Patent and making part of the same.

TO ALL WHOM IT MAY CONCERN:

Be it known that I, ROBERT ROOKE, of Empire City, Coos county, State of Oregon, have invented a new and improved Clothes-Washing Machine; and I do hereby declare that the following is a full, clear, and exact description thereof, which will enable others skilled in the art to make and use the same, reference being had to the accompanying drawing, forming part of this specification, in which—

Figures 1 and 2 are vertical central sections of my invention, the plane of one section being at right angles to that of the other.

Similar letters of reference indicate like parts.

This invention consists in a series of pounders arranged in connection with a rotating perforated tub, which is placed within a fixed or stationary tub, the pounders and rotating tub being operated from one and the same driving-shaft, and all arranged as hereinafter fully shown and described, whereby clothes may be cleansed very expeditiously and in a perfect manner.

A represents a tub, which may be of any suitable dimensions, and has two uprights B B, attached to it at opposite points, said uprights extending upward a suitable distance above the tub, and connected by cross-bars *a* at both sides. Within the tub A there is fitted a tub, C, which may be pivoted at the centre of its bottom as shown at *b*, and has casters or rollers, *c*, attached to the under side of its bottom to rest on the bottom of the tub A and obviate friction. The upper edge of the tub C is toothed as shown at *d*, and a pinion, D, gears into said teeth, as shown in both figures. E is a shaft, which has its bearings in the uprights B B, and has a horizontal position a short distance above the two tubs, said shaft having a series of tappets, *e*, attached, and also having a pinion, F, upon it which gears into the pinion D, the power being applied to the shaft E. The rods or bars *f* of pounders A', pass up between the cross-bars *a*, and the bars *a* are notched at their inner sides to receive vertical V-shaped ribs, *g*, which are secured to the rods or bars *f* of the pounders at two opposite sides thereof. By this means the pounders and their rods or bars are retained in proper position, and allowed to work freely up and down. The pounders are raised by the tappets *e* acting against projections *h* on the rods or bars *f*, and they fall by virtue of their own gravity. The pounders are raised consecutively or irregularly, so that there will be a continuous action upon the clothes, the tappets *e* being attached to shaft F with a view to that end. The bottom of the tub C is perforated, and the outer tub is provided with a faucet, *i*, to draw the water or suds from the tubs when desired. As the pounders operate the tub C is rotated by means of the gearing described, and hence all the clothes placed in the tub C will be equally operated upon. The bottom of the tub C is protected from the action of the pounders by stops *a*, attached to the pounder rods or bars *f* at the upper ends of the ribs *g*. I do not confine myself to any particular material. The tubs may be of wood, and the pounders may be of wood loaded if desired. The tappets *e* on shaft E may be of metal or hard wood, as well as the projections *h* on the pounder rods or bars *f*. This invention has been practically tested, and it operates well, cleansing the clothes expeditiously and in a thorough manner.

Having thus described my invention, I claim as new, and desire to secure by Letters Patent—

The pounders A', in combination with a rotary tub C, placed within a fixed tub A, and all arranged to operate substantially in the manner as and for the purpose herein set forth.

ROBERT ROOKE.
